Primary Examiner—Dominic Simone*(74) Attorney, Agent, or Firm*—Gifford, Krass, Sprinkle, Anderson & Citkowski, P.C.(57) **CLAIM**

The ornamental design for a shoe, as shown and described.

DESCRIPTION

FIG. 1 is a top plan view of a shoe showing my new design; FIG. 2 is a side elevational view thereof; FIG. 3 is a bottom plan view thereof; FIG. 4 is a front elevational view thereof; FIG. 5 is a rear elevational view thereof; FIG. 6 is a top plan view of a second embodiment of the shoe of FIG. 1; FIG. 7 is a side elevational view thereof; FIG. 8 is a bottom plan view thereof; FIG. 9 is a front elevational view thereof; and, FIG. 10 is a rear elevational view thereof.

The broken line showing of the sole in FIGS. 3 and 8 is for environmental purposes only and form no part of the claimed design.
